Primary Examiner — Karen S Acker

(74) Attorney, Agent, or Firm — William W. Letson

(57) **CLAIM**

The ornamental design for a paper with a pattern, as shown and described.

DESCRIPTION

The sole FIGURE is a top plan view of a paper with a pattern. The evenly spaced broken lines surrounding the design form the boundaries of the claim and form no part thereof. The thickness of the paper with a pattern forms no part of the claimed design.

1 Claim, 1 Drawing Sheet
